FURNACE WALL

Max H. Kuhner and Gustav A. Rehm, Worcester,
Mass., assignors to Riley Stoker Corporation,
Worcester, Mass., a corporation of Massachu-
sets

Application November 4, 1935, Serial No. 48,119

9 Claims. (Cl. 122—6)

This invention relates to furnace walls, and more particularly to walls of the type comprising spaced parallel tubes through which a cooling fluid is passed to prevent overheating of the wall.

It has been proposed to close the spaces between the tubes by means of blocks which in some cases extend around the inner or furnace sides of the tubes, but no thoroughly satisfactory means has heretofore been suggested for holding the blocks in place. With certain constructions it is necessary to remove the outer insulating casing of the wall in order to obtain access to the fastening means for the blocks. With other constructions the blocks are not held firmly against the tubes, and as a result overheating of the blocks occurs. With still other constructions it is necessary to weld lugs or other devices to the tubes, which has many disadvantages.

It is accordingly one object of the invention to provide an improved furnace wall of the type having spaced parallel tubes and blocks closing the spaces between the tubes, the parts being so constructed and arranged that the blocks can be installed and removed from the furnace side of the wall, and when the blocks are in place they will be held firmly against the tubes.

It is a further object of the invention to provide an improved furnace wall having tubes spaced comparatively closely together, and blocks closing the spaces between the tubes and readily installed or removed from the furnace side of the wall.

It is a further object of the invention to provide an improved block particularly adapted for closing the spaces between the tubes of a furnace wall.

It is a further object of the invention to provide an improved locking device particularly adapted for fastening blocks to the tubes of a furnace wall.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is an elevation of a portion of a furnace wall, viewed from the furnace side;

Fig. 2 is a section on the line 2—2 of Fig. 1;

Fig. 3 is a section on the line 3—3 of Fig. 2;

Fig. 4 is a perspective view of a block; and

Fig. 5 is a perspective view of a locking device.

In the drawing we have shown a furnace wall

comprising a row of spaced parallel vertical tubes 10 through which a suitable cooling fluid, such as water or steam, may be passed in a well-known manner to prevent overheating of the wall. The tubes are preferably spaced rather closely together in order to obtain a substantial cooling effect. For example, we have found that with tubes 3½ inches in outside diameter, and water as a cooling medium, a spacing of 4¼ inches between the centers of the tubes is satisfactory. Against the outer surface of the tubes there is provided a layer 11 of firebrick or other refractory material, and outside of the firebrick there is shown a layer 12 of a suitable heat insulating material. A casing 14 of sheet metal is mounted against the outer surface of the heat insulating layer 12.

Between each pair of adjacent tubes 10 there is provided a vertical row of blocks 15, the blocks being so shaped that they may be inserted between the tubes from the inner or furnace side of the wall. In the preferred construction the inner portion 16 of each block is widened to produce a block substantially T-shaped in cross-section, as shown particularly in Fig. 2, the lateral surfaces 17 of the blocks being concave to fit closely against the tubes at the inner side of the plane defined by the axes of the tubes.

In order to hold the blocks in position, we provide locking devices 19 which engage the surfaces of the tubes at the outer side of the plane defined by the axes of the tubes, and we preferably so construct these locking devices that the blocks will tend to slide over them under the influence of gravity and thus be forced outwardly against the tubes. For this purpose each block is formed with two recesses or notches 20 therein, one in the upper end of the block and one in the lower end of the block, and the outer wall 21 of each notch is sloped inwardly in a direction toward the center of the block. The locking devices 19 are shaped to provide upper and lower surfaces 23 which slope away from each other in the inward direction, and which at assembly contact with the sloping walls 21 and force the blocks outwardly against the tubes. These surfaces 23 are provided by flaring the inner portion of the device in a vertical plane. It will be noted from Fig. 3 that the locking devices 19 contact only with the outer walls 21 of the notches 20 and are spaced slightly from the inner walls of the notches, so that the blocks 15 are free to move outwardly into firm contact with the tubes. The outer portion of each locking device is flared laterally in a horizontal plane to provide concave surfaces 24 which

contact with the tubes at assembly. A slight clearance space 25 is provided between adjacent blocks 15 in each vertical row so that they may engage the locking devices firmly.

- 5 5 While it is possible, by decreasing certain dimensions of the locking devices 19, to construct each locking device in a single integral piece and still insert it between the tubes from the furnace side, this will necessitate some sacrifice in 10 strength and contact area, particularly when the tubes are closely spaced. For this reason we prefer to divide each locking device into two parts, each of which can be placed in position separately. In the preferred construction, each device 19 is divided into two sections along a central vertical plane perpendicular to the plane of the tube axes, each section of the device having a maximum thickness slightly less than the space between adjacent tubes.
- 20 20 In order to facilitate removal of the locking devices 19, they are preferably provided with transverse notches 27 on their inner faces. By inserting a small bar or lever in the notch 27 in one of the sections, it is a simple matter to pry this section 25 upwardly and remove the same, whereupon the other section and then the block beneath can be removed.

In mounting the blocks 15 on the tubes, it is considered desirable to start the blocks at the 30 bottoms of the vertical rows, these lowermost blocks being supported by any suitable means. The locking devices 19 can then be inserted, one section at a time, and dropped into place in the notches 20 in the upper ends of the blocks. The 35 next higher blocks can then be inserted and lowered until they rest upon the locking devices therebeneath. The weight of the blocks will cause the surfaces 21 to slide along the surfaces 23 on the locking devices and thus force the 40 blocks outwardly into firm contact with the tubes. This result will be brought about despite any slight inaccuracies in the tube spacing.

The construction is simple and inexpensive. The blocks can be inserted or removed entirely 45 from the furnace side of the wall, without any necessity for obtaining access to the outside of the wall or disturbing the casing and insulation. The refractory layer 11 can be placed in direct contact with the outside of the tubes without interfering with the blocks 15 or the locking devices 19.

Having thus described our invention, what we claim as new and desire to secure by Letters Patent is:

- 55 1. A furnace wall comprising a series of non-horizontal spaced parallel tubes, rows of blocks having concave surfaces which contact with the tubes at the inner side of the plane defined by the axes of the tubes, the blocks in each row being 60 slightly spaced apart, and locking means separable from the tubes and contacting with the tubes at the outer side of the said plane, the blocks engaging the locking means and these parts having cooperating surfaces so arranged 65 that movement of the blocks relative to the tubes and locking means in a direction parallel to the axes of the tubes under the influence of gravity will cause both the blocks and the locking means to move into firm contact with the tubes.
- 70 2. A furnace wall comprising a series of non-horizontal spaced parallel tubes, rows of blocks having concave surfaces which contact with the tubes at the inner side of the plane defined by the axes of the tubes, the blocks in each row being 75 slightly spaced apart, and a series of locking de-

vices mounted between the blocks and contacting with the tubes at the outer side of the said plane, the blocks and the locking devices having cooperating surfaces so arranged that when the blocks move toward each other under the influence of gravity the locking devices will pull the blocks outwardly into firm contact with the tubes.

3. A furnace wall comprising a pair of spaced parallel tubes, a row of blocks mounted between the tubes and slightly spaced apart, the blocks 10 contacting with the tubes at the inner side of the plane defined by the axes of the tubes, and a series of locking devices mounted between the respective blocks and contacting with the tubes at the outer side of the said plane, the blocks 15 and the locking devices having cooperating surfaces so arranged that when the blocks move toward each other the locking devices will pull the blocks outwardly into firm contact with the tubes.

4. A furnace wall comprising a pair of non-horizontal spaced parallel tubes, a row of blocks mounted between the tubes and slightly spaced apart, the blocks contacting with the tubes at the inner side of the plane defined by the axes of 25 the tubes, and a series of locking devices mounted between the respective blocks and contacting with the tubes at the outer side of the said plane, the blocks and the locking devices having cooperating surfaces so arranged that when the blocks move toward each other under the influence of gravity the locking devices will pull the blocks outwardly into firm contact with the tubes.

5. A furnace wall comprising a pair of spaced parallel tubes, a row of blocks mounted between the tubes and slightly spaced apart, the blocks being so constructed that they may be placed in position from the inner side of the wall and when in position they will contact with the tubes at the inner side of the plane defined by the axes 40 of the tubes, and a series of locking devices mounted between the respective blocks, the locking devices being so constructed that they may be placed in position from the inner side of the wall and when in position they will contact with the tubes at the inner side of the plane defined by the axes 45 of the tubes, and a series of locking devices mounted between the respective blocks, the locking devices being so constructed that they may be placed in position from the inner side of the wall and when in position they will contact with the tubes at the outer side of the said plane, the blocks and the locking devices having cooperating surfaces so arranged that when the blocks move toward each other the locking devices will pull the blocks outwardly into firm contact with 50 the tubes.

6. A furnace wall comprising a pair of spaced parallel tubes, a row of blocks mounted between the tubes and slightly spaced apart, the blocks being substantially T-shaped in cross-section and 55 provided with concave surfaces which contact with the tubes at the inner side of the plane defined by the axes of the tubes, and a series of locking devices mounted between the respective blocks and provided with concave surfaces which 60 contact with the tubes at the outer side of the said plane, the blocks and the locking devices having cooperating surfaces so arranged that when the blocks move toward each other the locking devices will pull the blocks outwardly into firm contact 65 with the tubes.

7. A furnace wall comprising a pair of non-horizontal spaced parallel tubes, a row of blocks mounted between the tubes and slightly spaced apart, the blocks being substantially T-shaped in 70 cross-section and provided with concave surfaces which contact with the tubes at the inner side of the plane defined by the axes of the tubes, each block having a transverse notch in each end with the outer wall of each notch sloping inwardly in a 75

direction toward the center of the block, and a series of locking devices mounted between the respective blocks and contacting with the tubes at the outer side of the said plane, the locking devices having surfaces which engage the said sloping outer walls of the notches, the locking devices being spaced slightly from the inner walls of the notches and the parts being so constructed and arranged that as the blocks move toward each other under the influence of gravity, they will be forced outwardly into firm contact with the tubes.

8. A furnace wall comprising a pair of non-horizontal spaced parallel tubes, a row of blocks mounted between the tubes and slightly spaced apart, the blocks being substantially T-shaped in cross-section and provided with concave surfaces which contact with the tubes at the inner side of the plane defined by the axes of the tubes, each block having a transverse notch in each end with the outer wall of each notch sloping inwardly in a direction toward the center of the block, and a series of locking devices mounted between the respective blocks and contacting with the tubes at the outer side of the said plane, the locking devices having upper and lower surfaces which slope away from each other in the inward direction and engage the said outer walls of the notches, the locking devices being spaced slightly from the inner walls of the notches and the parts being

so constructed and arranged that as the blocks move toward each other under the influence of gravity, they will be forced outwardly into firm contact with the tubes.

9. A furnace wall comprising a pair of non-horizontal spaced parallel tubes, a row of blocks mounted between the tubes and slightly spaced apart, the blocks being substantially T-shaped in cross-section and provided with concave surfaces which contact with the tubes at the inner side of the plane defined by the axes of the tubes, each block having a transverse notch in each end with the outer wall of each notch sloping inwardly in a direction toward the center of the block, and a series of locking devices mounted between the respective blocks and contacting with the tubes at the outer side of the said plane, the locking devices having upper and lower surfaces which slope away from each other in the inward direction and engage the said outer walls of the notches, the locking devices being spaced slightly from the inner walls of the notches and the parts being so constructed and arranged that as the blocks move toward each other under the influence of gravity, they will be forced outwardly into firm contact with the tubes.
